UNITED STATES PATENT OFFICE.

CHARLES F. GRAY, OF SIERRA MADRE, CALIFORNIA, ASSIGNOR TO THE SINGER
MANUFACTURING COMPANY, A CORPORATION OF NEW JERSEY.

SEWING-MACHINE.

1,115,663.

Specification of Letters Patent.

Patented Nov. 3, 1914.

Application filed November 25, 1911. Serial No. 662,301.

To all whom it may concern:

Be it known that I, CHARLES F. GRAY, a citizen of the United States, residing at Sierra Madre, in the county of Los Angeles 5 and State of California, have invented certain new and useful Improvements in Sewing-Machines, of which the following is a specification, reference being had therein to the accompanying drawings.

10 This invention relates to improvements in lock stitch sewing machines, and has for its object to improve the means employed for casting the loop of needle-thread about the mass of bobbin or under thread.

15 In the early forms of sewing machine constructions of the character above referred to, there was employed in combination a rotary loop-taker having variable motion and provided with a substantially long loop-seizing 20 point, in connection with a substantially long point needle and cam-actuated take-up, which form of construction was in many respects superior to the later constructions, as the long point loop-taker permitted the 25 withdrawal of the needle eye out of the fabric while the point of the loop-taker was entering the loop, the cam-actuated take-up served to guard the needle-thread loop against being entered a second time by the 30 loop-seizing point of the loop-taker, and the long point needle made it much easier to pierce fabrics of substantially firm texture, but owing to the employment of the cam-actuated take-up such constructions were not 35 adapted to the high speed of 3000 or 4000 stitches per minute common in connection with the present high speed sewing machines.

To effect the high speed of the present 40 machines, link take-ups were introduced in connection with so-termed "short point" needles and "short point" rotary loop-takers, the latter being given one effective or loop-seizing and one idle rotation to one 45 complete actuation of the needle, such form of needles and loop-takers being necessary to accommodate the action of the link take-up. The more desirable form of construction, however, comprises the combination of 50 long point loop-takers, long point needles and link take-ups, together with means for assisting the take-up to disengage the needle-thread loop from the loop-seizing point of the loop-taker before the latter commences 55 its idle rotation, and to meet these re-

quirements the loop-taker is provided with a wall loop-disengaging which latter engages the needle-thread loop as it is about to be cast free from the bobbin and controls a sufficient amount of needle-thread to remove its loop from the loop-seizing point of the loop-taker prior to the latter completing its effective rotation, as illustrated in Fig. 8, so that said loop will be free to be acted on by the take-up during the idle rotation of 60 said loop-taker, thus making it practical to employ the more desirable form of loop-seizing point and needle point and dispense with the cam-actuated take-up which, as previously stated, is not adapted to high 65 speed.

Referring to the accompanying drawings, in the several figures of which like parts are similarly designated, Figure 1 is a front side elevation of one form of commercial 75 sewing machine equipped with the present invention. Fig. 2 is an underside view of Fig. 1. Fig. 3 is a plan view of the front end of the sewing machine bed-plate shown in Figs. 1 and 2, partially broken out to 80 better illustrate the mounting of the loop-taker. Figs. 4, 5, 6, 7, 8 and 9 illustrate the relative action of the loop-taker and take-up at various stages in the formation of the stitch, the arrows indicating the direction of movement of the take-up at the time the thread loop is in the position illustrated in the same figure. Fig. 10 is a plan view of the loop-taker, showing the needle-thread about to be released from the control 85 of the loop-taker. Figs. 11 and 12 are plan views of the loop-takers shown in Figs. 4 and 5. Fig. 13 comprises an underside view and a view in central section of the back 90 slide plate shown in Fig. 1.

The present invention is shown as applied to a Singer 109^w class machine (compound feed), but as it deals principally with the construction of the loop-taker, only such reference will be made to the other elements 100 of the machine as is deemed necessary for a proper understanding of its application.

Referring to the figures, 1 represents the bed-plate of the sewing machine upon which is mounted the bracket arm comprising the 105 arm bracket 2 and standard 3, 4 the main or needle-bar-driving shaft provided at its rear end with a band or hand wheel 5 and at its opposite end with a shaft flange 6 to which is pivotally attached the needle-bar- 110

actuating link 7 connected by a suitable pinch collar, as 8, with the needle-bar 9 carrying the eye-pointed needle 10, 11 the needle-thread tensions and 12 the needle-thread take-up, the latter being pivoted upon a stationary portion of the bracket arm and actuated from a connection 13 carried by the needle-bar-actuating link.

14 represents the commonly-employed cloth-presser bar carrying at its lower end the cloth-presser 15 of one form of well-understood construction.

16 represents the looper-actuating shaft mounted in suitable bearings located at the underside of the bed-plate of the sewing machine and connected with the main or needle-bar-actuating shaft by suitable crank connections, as 17, said loop-taker-actuating shaft carrying near its forward end a spiral gear 18 which meshes with a like gear 19 carried by the loop-taker shaft 20, and as the ratio of said gears is as two to one, the loop-taker is given one idle and one effective or loop-seizing revolution to one revolution of said main shaft, as is common in connection with machines employing a loop-taker having two revolutions to one of the main shaft.

21 represents the feed drive shaft connected at its rear end by an arm 22 with a feed connection 23 whose upper end is connected in the usual manner with a suitable eccentric (not shown) carried by the main shaft, the forward end of said feed drive shaft carrying the commonly-employed feed-bar 24 provided with a feed-dog 25 and with a forked end 26 which embraces an eccentric 27 carried by the looper-actuating shaft 16, thus, through the action of the shaft 21, horizontal movements are transmitted to the feed-dog 25 and, through the action of the eccentric 27, said feed-dog is moved vertically in a manner common to four-motion feeding mechanisms, but as the present invention does not rely for its effective action upon the character of the feeding mechanism employed, further reference to the latter is deemed unnecessary.

While not essential, it is desirable in connection with a rotary loop-taker to employ mechanism for insuring that the needle-thread will have a free passage about the bobbin, and in the present instance there is employed well-understood means comprising a rigid stop member 28 against which the shoulder 29 of the bobbin-case 30 rests, except at such time as the free end of the lever 31 is actuated, through suitable connections, as 32, operated by an eccentric 33, to move the projection 34 of the bobbin-case 30 in a direction opposite to that of the rotation of the loop-taker, thus separating the elements 28 and 29 for the passage of the needle-thread as it is cast about the periphery of 65 the bobbin-case at the side opposite the line

of needle actuation, when the eccentric 33 acts on the lever 31 to move its free end out of engagement with the projection 34 when, through the frictional contact of the loop-taker with the bobbin-case, the shoulder 29 is again brought into contact with the stop 28, thus effecting the opening 35 for the passage of the needle-thread as it is drawn by the take-up from engagement with the loop-taker, a stationary stop 36 acting to limit the movement of the projection 34 when acted on by the free end of the lever 31, the same as is represented by U. S. Patent No. 1,000,797, dated August 15, 1911, with the exception that in the patent the loop-taker is mounted to rotate in a vertical plane instead of in a horizontal plane, as in the present construction.

All of the foregoing parts are commonly found in sewing machines of the present class, and are herein shown as best representing one form of construction to which the present invention is applicable.

In the present instance, the bobbin-case is retained in the rotary loop-taker 37 in a manner common to rotary loop-takers employing a centrally located non-rotating bobbin-case, and the bobbin 38 is held against accidental vertical movement in the bobbin-case 30 by a projection 39 formed on the underside of the slide plate 40 (see Fig. 1).

In Figs. 4 and 11, the loop-seizing point 41 is shown as having just entered the loop of the needle-thread in the formation of a stitch, in Figs. 5 and 12 the loop-taker is shown advanced sufficiently to carry the loop of the needle-thread to the base or throat 41' of the loop-seizing point 41, and in Fig. 6 the loop-taker is shown advanced to a position where it is about to cast the loop past the diameter of the bobbin intersecting the line of needle actuation, and it is substantially at this point in the formation of the stitch that the loop-disengaging member comprising the wall 42 extending inward from the face or outer surface of the loop-taker engages the loop of needle-thread, as shown in Fig. 7; and during the further rotation of said loop-taker the take-up and wall 42 act to draw the thread loop off the loop-seizing point of the loop-taker, back of the guard 44 and onto the finger 43, as shown in Fig. 8, the guard 44 being formed integral with the commonly employed hook-washer 45 provided with the needle-guard 46. In the rotation of the loop-taker from the position shown in Fig. 8 to that shown in Fig. 9, the wall 42 is carried out of operative relationship with the thread loop, leaving the latter out of the path of travel of the loop-seizing point of the loop-taker, as shown in the figure last referred to; and in the continued operation of the loop-taker its loop-seizing point is carried 130

past the line of vertical movement of the thread loop in its travel into the fabric, as shown in Fig. 10. It will thus be obvious that the loop-disengaging wall 42 acts to control sufficient of the needle-thread loop, after it has been cast about the bobbin by the action of the loop-taker, to insure that the take-up will control said loop so that it will be drawn off the loop-seizing point of the loop-taker prior to the latter completing its effective rotation.

Claims:-

1. In a sewing machine, the combination with fabric - feeding and stitch - forming mechanism including a rotary main-shaft, a loop-taker shaft having multiple rotations to one of said main-shaft, and a needle-thread take-up operated from the actuating mechanism of the sewing machine through a link connection, of a loop-taker carried by said loop-taker shaft and provided with a loop-seizing point, and a needle-thread-loop-disengaging wall, the latter and the take-up acting to draw the needle-thread loop off the loop-seizing point of the loop-taker before the latter completes its effective rotation.
2. In a sewing machine, the combination with fabric - feeding and stitch - forming mechanism including a rotary main-shaft, a loop-taker shaft having multiple rotations to one of said main-shaft, and a needle-thread take-up operated from the actuating mechanism of the sewing machine through a link connection, of a loop-taker carried by said loop-taker shaft and provided with a

loop-seizing point and a needle-thread-loop-disengaging wall, the latter inclined inwardly from the face of said loop-taker, said loop-disengaging wall and take-up acting to draw the needle-thread loop off the loop-seizing point of the loop-taker before the latter completes its effective rotation.

3. In a sewing machine, the combination with fabric - feeding and stitch - forming mechanism including a rotary main-shaft, a loop-taker shaft having multiple rotations to one of said main-shaft, and a needle-thread take-up operated from the actuating mechanism of the sewing machine through a link connection, of a loop-taker carried by said loop-taker shaft and provided with a loop-seizing point, a finger and a loop-disengaging wall, the latter and said take-up acting to draw the needle - thread loop off said loop-seizing point before the loop-taker completes its effective rotation, and the further action of said loop-taker and take-up causing said loop to be engaged by said finger until the latter is withdrawn by the rotation of the loop-taker, when said needle-thread loop is drawn by the action of the take-up to its stitch-forming position.

In testimony whereof, I have signed my name to this specification, in the presence of two subscribing witnesses.
